[57] **CLAIM**

The ornamental design for a divider for bottles, as shown and described.

DESCRIPTION

FIG. 1 is a top plan view of a divider for bottles showing our new design;
 FIG. 2 is a bottom plan view thereof;
 FIG. 3 is a front elevational view thereof the rear elevational view being a mirror image thereof;
 FIG. 4 is a right side elevational view thereof;
 FIG. 5 is a cross sectional view taken along line 5—5 of FIG. 1;
 FIG. 6 is a partial cross-sectional view taken on line 6—6 of FIG. 1;
 FIG. 7 is a partial cross-sectional view taken on line 7—7 of FIG. 1;
 FIG. 8 is an enlarged cross-sectional view taken on line 8—8 of FIG. 1 and,
 FIG. 9 is a left side elevational view thereof.

FIG. 1

FIG. 2

FIG. 3

FIG. 4

FIG. 6

FIG. 4

FIG. 5

FIG. 7

FIG. 8

FIG. 9
